UNITED STATES PATENT OFFICE.

FRANKLIN H. BURR, OF ATLANTIC, IOWA.

MAIL RECEIVING AND DELIVERING MECHANISM FOR RAILWAYS.

SPECIFICATION forming part of Letters Patent No. 761,874, dated June 7, 1904.

Application filed July 15, 1903. Serial No. 165,712. (No model.)

To all whom it may concern:

Be it known that I, FRANKLIN H. BURR, a citizen of the United States, residing at Atlantic, in the county of Cass and State of Iowa, 5 have invented certain new and useful Improvements in Mail Receiving and Delivering Mechanism for Railways, of which the following is a specification.

This invention relates to receiving and delivering mechanism for railway-cars, and has for its object to use compressed air taken from the train-pipes or steam from the steam-pipes to operate the delivering devices and to provide means whereby compressed air or 15 steam will be automatically admitted to the operating mechanism to actuate said delivering devices.

It is further intended to provide a simple, durable, and efficient construction and one 20 which is readily adaptable to mail-cars now in use.

In the drawings, Figure 1 is a perspective view of a portion of a railway-car, showing the application of the device thereto and the 25 arrangement of the auxiliary apparatus at the side of the track; Fig. 2, a bottom plan view of the car, showing the arrangement of the air pipes, cylinders, and levers; Fig. 3, a vertical cross-section of the car-body and equipment 30 along line 3 of Fig. 2, and Fig. 4 a perspective view of the operating-levers.

In the drawings, 1 denotes a car; 2, the swinging crane or bag-catcher arranged across the door in the usual manner and having an 35 inwardly-projecting handle 2'.

3 denotes the stationary catcher-post or crane at the side of the track, and 4 a receiving-box or housing having a door 5 at one end secured by hinges at its upper end and 40 adapted to swing inwardly, and leading forwardly from the door-sill and parallel with the track is a floor 6, having on each side guard-rails 7, the floor and guide-rails being designed to catch the mail-bags as they are 45 delivered thereto by the mechanism hereinafter described.

The delivering-frame 8, hinged or pivoted in the doorway of one side of the car, is a rectangular frame having an apron 9, and the 50 inner end has a bail 10 and connecting-rod 10',

which is hinged to the inner end of the handle 2'. Midway between the ends this frame is hinged to the vertically-disposed limbs 11 of a horizontal bar 12 at brackets 13, secured to the side of the car. A fixed depending arm 55 14 is pivotally connected with a lever 15, which extends horizontally beneath the car-body and is connected at its opposite end with a piston-rod 16 of a piston adapted to work within an air-cylinder 17 beneath the car. Each side of 60 the car is similarly equipped to operate in opposite directions for actuating the delivering-frame at either side of the car. The rods 16 extend beyond the ends of the cylinders, being supported in guide-brackets 18, depending 65 from the car. In operation the delivery-frame 8 when thrown outwardly or dumped, so it falls down and rests vertically alongside the car-body, draws down the arm 2', which correspondingly throws up or out the catching-arm 2 so it is in position to catch the bag 70 on post 3. By this arrangement a single manual operation is required to manipulate the air-valve levers for desired purposes.

The receiving-box 4 is made air-tight when 75 closed except at the door thereof, and the latter swinging inwardly compresses the air in the box, thus providing an air-cushion which greatly breaks the impact of the mail-bag as it strikes the door 5.

A longitudinally-disposed pipe 22 is located on each end of the air-cylinders 17, both pipes being connected at one end by a branch 23 with an air-reservoir 19, the other respective 80 ends of the pipes 22 being connected with the 85 opposite ends of the cylinders 17 in such manner that when air is admitted to pipes 22 from the air-reservoir the piston-rods 16 will move inwardly. This reservoir is beneath the car and is connected by a branch pipe 20 with the 90 train-pipe 21, which supplies air to the brake-cylinders. A check-valve 20' is placed in branch pipe 20 to prevent air in reservoir 19 from flowing toward the train-pipe during the 95 braking operation. On a line with one of the 95 jams 24 of the door the pipes 25 are provided with valves, each of which is adapted to be operated by a lever 26. These levers have each a link 27, which is connected with the right-angled arm 28 on the lower end of 100

the vertical bar 29, which extends up through the floor of the car, terminating in a right-angled arm 30. Parallel with this bar is a similar bar 31, also provided with a right-angled arm 32, the upper ends of both bars being held by a bracket 33, attached to the inside of the car. The lower end of the bar 31 has a horizontal arm 34, which when the bar is swung around will project out beyond the side of the car and engage with an adjustable arm 35, hinged to a post 36. This adjustable arm has a buffer-head 37, against which the arm 34 engages as the car passes by, and the object is to cause the movement of the car to swing the arm around, and thus operate the air-valves, as will now be explained.

The upper ends of the bars 29 31 have segmental toothed wheels 38 39, which are adapted to engage with each other, the segment 39 having a flange 40 above the teeth 41, so that the teeth 42 of the segment 38 will rest beneath the flange 40 when the teeth of the two segments are in engagement with each other. Normally the segment 38 is above the segment 39, as shown, for instance, in Fig. 3; but when the arm 34 is to be set the rod 31 is turned and depressed so that the segment 38 rests under the flange 40 with the teeth of the two segments in engagement with each other. The bottom view, Fig. 2, shows the arrangement of the segments and arm 34 when properly set. When in this position, the valve 25 is closed, and when the arm 34 strikes against the buffer-head 37 of the arm 35, the arm 34 is swung around, as indicated by the dotted lines 44, and the result is that the rod 29 is turned, swinging its arm 28 to the position shown by dotted line 45, thus opening the valve 25, admitting steam to the air-cylinder 17, so as to actuate the piston-rod 16, which draws the outer end of the mail-bag frame 8 inwardly, with sufficient force to throw the mail-bag from its resting-place on the apron 9 and deposit it into the chute 6 7. A coiled spring 46 on the vertical bar 31 serves to throw back the arm or to hold it beneath the car as soon as the segments are disengaged from each other.

In the pipe 22, between the valve 25 and the air-cylinder 17, is a relief-valve 47, the stem of which is attached to an operating-cord 48, which passes up through the floor of the car to a point within reach of the operator, the object being to provide an exhaust for the cylinder 17, so that the piston may again be thrown outwardly and the mail-bag frame returned to its normal position.

While I have described the invention as connected up with the train-pipe and using the brake-air, I may, if desired, connect the same with the signal-pipes, or steam may be used directly from the steam-pipes or the engine. When connected up with the train or signal or steam pipes, the air in said pipes may be used in the usual manner, as the reservoir 19

always contains enough air under sufficient pressure to operate the mechanism, and the air used from the line of pipe 21 will not interfere with the train or signal pipes connected therewith should the air in them be used for 70 braking or signaling purposes.

From the foregoing description, taken in connection with the accompanying drawings, the construction, mode of operation, and advantages of my invention will be readily understood, and various changes in the form, proportion, and minor details of my invention may be resorted to without departing from the spirit of my invention or sacrificing any of the principles or advantages thereof. 80

What I claim as new is—

1. In a delivering mechanism for railway-cars, the combination of a delivering-frame having a pivotal attachment to said car, an air-cylinder having a piston therein, connected with said delivering-frame, levers for operating same and means for automatically actuating said levers whereby said delivery-frame is tilted or dumped, substantially as set forth. 85

2. In a delivery mechanism for railway-cars, the combination of a delivering-frame having a pivotal connection with said car, an air-cylinder having a piston therein connected with said delivery-frame, levers for operating same and fluid-pressure mechanism for automatically actuating said levers whereby said delivery-frame is tilted or dumped, substantially as set forth. 90

3. In a delivery mechanism for railway-cars, the combination of a delivering-frame having a pivotal connection with said car, an air-cylinder having a piston therein connected with said delivery-frame, fluid-pressure mechanism for actuating the piston whereby said delivery-frame is tilted or dumped, a compressed-fluid reservoir connected with said fluid-pressure mechanism, means for automatically controlling the admission of said fluid to said fluid-pressure mechanism, and means for exhausting said air-cylinder, substantially as set forth. 100

4. In a delivery mechanism for railway-cars, the combination of a delivering-frame having a pivotal connection with said car, an air-cylinder having a piston therein connected with said delivery-frame, a compressed-fluid mechanism for actuating the piston to tilt and dump said frame, a compressed-fluid reservoir connected with said fluid-pressure mechanism, a relief-valve for exhausting the said compressed fluid from said air-cylinder, a valve for controlling the admission of said fluid to said fluid-pressure mechanism, and means for automatically opening said valve, substantially as set forth. 115

5. In a delivering mechanism for railway-cars, the combination of a delivering-frame having a pivotal connection with said car, an air-cylinder having a piston therein connected with said delivery-frame, and fluid-pressure 120

125

130

mechanism for actuating the same, a swinging arm on the car adapted to be thrown out to engage with a stationary object and mechanism between said swinging arm and the 5 fluid-pressure mechanism, whereby the swinging of said arm will set in operation said fluid-pressure mechanism and tilt or dump the delivery-frame, as set forth.

6. In a delivery mechanism for railway-cars, the combination of a delivery-frame having pivotal connection with said car, an air-cylinder having a piston therein connected with said delivery-frame and fluid-pressure mechanism for actuating same, a pair of parallel vertical bars extending up into the car, adjustably geared to each other by segmental gearing, one of said bars being connected up with and adapted to control the air-supply to said air-cylinder, and the other bar having at its 20 lower end a right-angled arm to swing out from the car and adapted to actuate the bar controlling the air-supply, as set forth.

7. In a mail-delivery mechanism, a mail-receiving box adjacent to a railway-track having on one side a door hinged at its upper end and adapted to swing inwardly, a chute with an inclined floor leading down from said door and parallel with the railway-track and mechanism near the ends of said chute for actuating the car mechanism, whereby the mail-bag on said mechanism will be deposited on said inclined floor and delivered to said receiving-box, as set forth.

8. In a mail-delivery mechanism, a closed 35 mail-receiving box adjacent to a railway-track, having at one side a door hinged at its upper end and adapted to swing inwardly, said closed box and operating-door constituting a pneumatic means for checking the impact of the 40 mail-bag, in combination with an inclined floor and chute leading to the door of the box, and means for delivering a mail-bag to the inclined floor.

9. In mail-delivering mechanism, a post adjacent to a railway-track, having thereon a 45 swinging arm and means for holding the same at any suitable angle, a buffer-head on the end of said arm and a mail-car and means for engaging with said buffer-head, substantially as set forth. 50

10. In mail-delivering mechanism, a post adjacent to a railway-track, having thereon a swinging arm and means for holding the same at any suitable angle, combined with a chute parallel with said railway-track and in line 55 with said post, a mail-receiving box at the opposite end of said chute, and mail-car having mechanism thereon to engage with said buffer-head and deliver mail-bags to said chute.

11. In delivery mechanism for railway-cars, 60 the combination of a mail-car, having across the door thereof a horizontal rocking bar with a bag-catching arm and an operating-handle thereon, a delivery-frame below said arm, hinged to the side of the car, the rear end of 65 said frame and the handle of the catching-arm being operatively connected together, and means beneath said car for dumping said delivery-frame and setting said catching-arm, as herein set forth. 70

12. In a delivery mechanism for railway-cars, the combination in a mail-car of swinging dumping-frames for delivering mail-bags, air-cylinders connected with said dumping-tables and means for operating same, means 75 for venting said air-cylinders from the car, a reservoir connected with the train-pipes and with said air-cylinders, and a check-valve in the branch from the train-pipe to the air-reservoir, substantially as set forth. 80

In testimony whereof I affix my signature in presence of two witnesses.
